UNITED STATES PATENT OFFICE.

FLOYD MONROUGH CRANK, OF MUSKOGEE, OKLAHOMA.

AUTOMOBILE-LOCK.

1,284,608.

Specification of Letters Patent. Patented Nov. 12, 1918.

Application filed July 3, 1917, Serial No. 178,391. Renewed April 24, 1918. Serial No. 230,615.

To all whom it may concern:

Be it known that I, FLOYD MONROUGH CRANK, a citizen of the United States of America, residing at Muskogee, in the county of Muskogee and State of Oklahoma, have invented certain new and useful Improvements in Automobile-Locks, of which the following is a specification.

My invention relates to improvements in automobile locks of the type wherein the control lever is locked in reverse gear.

It has heretofore been customary to lock an automobile so as to prevent same being moved, and in case of fire or other disturbance if it was found essential to remove the vehicle, it was necessary to push or slide it, or lift it bodily to another place. In other cases means have been provided to lock the control lever in neutral, which while permitting of the removal of the vehicle manually, it was impossible to move it by means of its own power.

According to my invention, I provide means for locking the control lever in reverse position; consequently when it is found necessary to move the car, for instance in case of fire or other unusual disturbance, the clutch can be disengaged and the engine started in the usual way, and the car by its own power can be backed to a point of safety and yet for ordinary purposes stealing is prevented.

The invention, therefore, comprehends improvements in the details of construction and arrangements of parts which will be hereinafter described and particularly pointed out in the claims.

In the drawings:—

Figure 1 is perspective view of the lock applied.

Fig. 2 is a plan view of same.

Fig. 3 is a vertical section of the lock.

Fig. 4 is a section on the line 4—4, of Fig. 3.

Fig. 5 is a section on the line 5—5, of Fig. 3.

1 indicates the ordinary control lever used to shift the usual transmission gears, and 2 is the plate having the slots to guide the lever.

3 indicates my improved lock, and it comprises a casing 4, provided at the top with an overhanging flange 6, and a depending reduced portion 7, one side of the latter

being beveled to rest on the control lever 55 when the same is thrown in reverse position in the slot formed in the plate.

A recess 8 is formed in the depending reduced portion, and mounted therein, on a pivot 9, is a dog 10, the upper outer end 11 60 of which is adapted to be projected beyond the plane of the face of the reduced portion, as will presently appear. Extending from the top portion of the dog 10, and spaced from the end 11, is a cylindrical 65 projection 12, and engaging same is the eye 13, of reciprocating rod 14, which is mounted in an opening 15 formed in the casing. On one side of the rod 14, are teeth 16, with which teeth 17, on a key 18, mesh when 70 operating the dog, the key fitting in a vertical opening 19 in the top of the casing.

A spring 20 is located in the recess 8, and is interposed between the inner edge of the dog 10, and the wall of said recess to normally rock the dog on its pivot and project the upper end beyond the plane of the face of the depending reduced portion. A shield 21, is fitted over the face of the depending reduced portion to protect the dog and prevent unauthorized persons from tampering with the lock.

In operation, the key is inserted in the vertical opening, and its teeth mesh with the teeth on the rod, and by turning the key the 85 dog is withdrawn against the tension of the spring.

In the meantime, the control lever 1, is shifted in the slot in plate 2, to reverse position. Then the depending reduced portion 90 is inserted in the slot, and in the shield, the overhanging flange 6, resting on the top of the plate 2, and a recess 4^a, on the casting, engages the yoke 1^a on the control lever 1. The key is turned, or rather pressure thereon is removed, and the spring rocks the dog 95 and projects its upper end 11, beyond the face of the casting and under the edge of the plate 2. It follows that inasmuch as the opposite edge of the casting is confined by 100 and is in engagement with the control lever and the yoke, and as the upper end 11 is caught under the plate 2, the lock cannot be withdrawn, nor can the control lever 1 105 be moved in the slot. Hence, the car is locked in reverse gear and affords protection against theft, but if it should be necessary to back the car from a curb or its

stored position in the garage, the clutch can be disengaged and the engine started and the car backed by its own power.

What I claim is:—

- 5 1. An automobile lock to lock a control lever in interlocked gear position comprising a casing, a pivoted dog normally projected beyond the face of the casing, a flange on the casing to coöperate with the pivoted dog to lock the lever in interlocked gear position, a rod extending from the dog, teeth on the rod, interlocking means between the casing and the control lever, and a key having teeth to mesh with the teeth on the 10 rod to retract the dog to remove the lock.
- 15 2. An automobile lock comprising a casing having a top overchanging flange and a depending reduced portion formed with a recess, a dog pivoted in the recess, a spring for normally projecting the upper end of the dog to coöperate with the flange to hold the lock in locking position, a rod pivotally connected to the upper end of the dog and mounted to reciprocate in an opening 20 formed in the casing, said rod having teeth on one edge, and a key having teeth near one end to engage the teeth on the rod to withdraw the dog in the recess to unlocked position.
- 25 3. An automobile lock comprising a casing having a top overlapping flange and a reduced depending portion formed on one 30

edge with a recess, a dog mounted in the casing to be projected beyond the edge of said casing when in locking position which with the recess and overlapping flange prevents the removal of the lock when fitted to the control lever of an automobile, and a key for withdrawing the dog to remove the lock.

4. An automobile lock comprising a casing having a recess in one side edge thereof, a dog mounted in the casing which projects beyond the face of the casing when in locking position which with the recess prevents the removal of the lock when fitted to the control lever of an automobile, and a key for withdrawing the dog to remove the lock.

5. An automobile lock comprising a casing having a flange, a dog adapted to be projected beyond the flange to form an interlock, the casing being formed to interlock with the control lever to coöperate with the flange and the dog to hold the lock in position to prevent movement of the lever, and a key for withdrawing the dog to remove the lock.

In testimony whereof I affix my signature in the presence of two witnesses.

FLOYD MONROUGH CRANK.
